Application July 2, 1937, Serial No. 151,618
In Great Britain July 8, 1936

12 Claims. (Cl. 250—20)

This invention relates to modulated carrier wave receivers. The invention has particular, but not exclusive application to modulated carrier wave receivers of the superheterodyne type.

Various attempts have been made with a view to providing means for varying the selectivity of receivers, either manually, or automatically with the strength of the received signals, and in cases where selectivity is controlled automatically, it has been proposed to employ a valve shunted across the circuit the selectivity of which is to be controlled, the valve being fed with rectified currents, corresponding to the received signal strength for varying its shunting effect whereby the response curve of the circuit is likewise varied. Such an arrangement is, however, expensive owing to the provision of the additional valve shunting the circuit.

It is the chief object of the present invention to provide an improved circuit whereby variations of the selectivity can be obtained either manually or automatically as the signal strength varies, or by a combination of automatic and manual means.

It is also an object of the invention to provide a receiver which will give a balanced reproduction of sound signals even when the selectivity is varied.

According to one feature of the invention, a modulated carrier wave receiver is provided comprising a thermionic valve provided with means for effectively producing a wholly or partially negative feed back of voltage to a control electrode of the valve, the magnitude of the feedback varying with frequency for the purpose of modifying the frequency response of the receiver and means for changing the operating characteristics of said valve whereby the effect of the voltage feedback is modified. Preferably, the effect of the feedback on the frequency response of the receiver is modified by varying the slope of the valve by variation of the bias potential, and where automatic selectivity is required this may be effected by applying to one of the control electrodes of said valve volume or gain control bias potentials, derived in known manner.

If desired the said valve may be included in a stage of amplification associated with another stage of amplification including another thermionic valve so linked with the first mentioned valve, that the change in the gain of each amplifier stage under the action of the volume or gain control bias potential is different in each stage, whereby the effect of the negative feed back can be controlled independently of the

amount of applied automatic volume control bias, and means may be provided whereby the distribution of volume control bias potentials to each of the two linked stages may be adjusted manually.

An arrangement according to the invention may also be used to adjust the balance of reproduced sound, in a receiver where the selectivity is changed as the strength of the received signals changes. In this case the feedback according to the invention may operate on the low or bass frequencies of the reproduced sound in a manner corresponding to the way in which the high frequencies thereof are affected by the variation of the selectivity.

The feedback of voltage according to the invention may be obtained from an impedance which is common to the anode-cathode path and to the control grid-cathode path of the valve, said impedance being arranged to be of low value for one frequency in the signal band and of higher values for the frequencies in the signal band remote from that frequency. In a carrier wave receiver of the superheterodyne type in which the invention is applied for producing automatic variation of selectivity with varying signal strength, the invention will usually be applied to a stage of intermediate frequency amplification and the aforesaid impedance will usually be made of low value for the intermediate frequency of the receiver. In a superheterodyne receiver a selectivity control according to the invention may be applied to the frequency changer valve of the receiver. In other carrier wave receivers the invention will usually be applied in connection with a stage of carrier frequency amplification.

In order that the said invention may be clearly understood and readily carried into effect, the same will now be described with reference to the accompanying drawings in which:

Figs. 1 and 2 illustrate circuits embodying the basic principles of the invention,

Figs. 3A, 3B, 3C and 3D illustrate modifications of the cathode circuits of the arrangements shown in Figs. 1 and 2 and Figs. 4 to 9 illustrate further embodiments of the invention. In the drawings similar components are indicated by the same reference numerals.

Referring now more particularly to Fig. 1 of the accompanying drawings, the reference numerals 1 and 2 represent respectively the input and output circuits of an intermediate frequency amplifying valve 6, shown as a screened grid valve of the variable mu type, the invention, as

will be appreciated, being described for use in a superheterodyne receiver. The invention is also described in this figure in conjunction with automatic volume or gain control the purpose of which will be hereinafter more fully explained.

The input circuit 1 is coupled to the control grid of the valve 6 and is decoupled to earth by a condenser 3, automatic volume or gain control potential derived in any suitable manner being applied to the control grid of valve 6 through resistance 4 from a line 5 denoted by the letters A. V. C. Negative feed back for the valve 6 is obtained by the provision of an inductance 7a and series condenser 7b in the cathode lead of the valve 6, the feed back circuit being generally designated by the dotted line rectangle 7. For the purpose of by-passing anode current a choke 8 is provided in parallel with the circuit 7, the choke 8 being roughly tuned if desired with the parallel condenser shown. The circuit 7 is arranged to present a low impedance at its resonant frequency as by tuning the circuit to the same frequency as the circuits 1 and 2 which, in the case of a superheterodyne receiver, corresponds to the intermediate frequency of the receiver. At this frequency a small negative feed back is provided by the residual resistance of the circuit 7, and for side-band frequencies the impedance of the circuit 7 increases, thus reducing the gain for such side-band frequencies. If the slope or mutual conductance of the valve is high, the feed back will attenuate or cut off the side-bands, but at low slopes the effect of the feed back will be negligible. In the example of Fig. 1 the slope of the valve measured in terms of cathode current will be the combined slope to screen and anode, but in the example shown in Fig. 2 which illustrates a modification of that shown in Fig. 1, and in which like reference numerals indicate similar parts, the slope of the valve is only the slope to the anode. In Fig. 2 it will be observed that the circuit 7 is coupled to the output circuit 2 through an anode circuit decoupling condenser 9. Assuming the slope of the valves of Figs. 1 and 2 to be g , and z the impedance of the circuit 7 with the choke 8 in parallel therewith, then the effective slope of the valve in the presence of the negative feedback will be

$$\frac{1}{\frac{1}{g} + z}$$

or the effective ratio of the slopes with and without negative feed back will be

$$\frac{\frac{1}{g}}{\frac{1}{\frac{1}{g} + z}} = \frac{1}{1 + gz}$$

As stated above, z is small at carrier frequencies and larger at side-band frequencies, so that, providing z is sufficiently great, there will be an attenuation or cut-off of side-band frequencies and a corresponding increase of selectivity. This increase in selectivity will be most noticeable when g is large, that is to say, when there is little automatic volume control negative bias as when distant stations are being received. On a local station the automatic volume control voltage will increase the bias thus reducing the slope of the valve and so making the negative feedback, and hence the extra selectivity, negligible. Thus it will be appreciated that with the circuits shown in Figs. 1 and 2, automatic variable selectivity occurs, the selectivity decreasing when local sta-

tions are being received and increasing with more distant stations. It will be understood that instead of employing the automatic volume control to vary the slope of the valves 6 for selectivity control, the bias on the valves may be adjusted manually, or alternatively, a manual control may be employed in addition to the automatic volume control potentials so that the slope of the valves may be maintained high thereby extra selectivity is available for a less distant station which is subjected to unusually severe interference.

The circuit 7 of Figs. 1 and 2 may be replaced by the circuits shown in Figs. 3A, 3B, 3C and 3D. In Fig. 3A an inductance 7c is bridged across the condenser 7b so as to by-pass the anode current thus obviating the use of the inductances 8 of Figs. 1 and 2. The inductance 7c may be made sufficiently high to avoid a parallel resonance with the associated condenser 7b within the working range, the circuit shown in Fig. 3A being tuned by the condenser 7b so as to present a low impedance at the carrier or intermediate frequency for the reasons referred to above.

In Fig. 3B the circuit 7 is replaced by a condenser 7d shunted by an inductance 7c in series with another condenser 7f shunted by an inductance 7g. The circuit of Fig. 3B can be adjusted to present a low impedance at the carrier frequency and a high impedance at two frequencies on either side of the carrier frequency so that a comparatively sharp cut can be effected at the undesired side-band frequencies without necessitating the high coil efficiency required in the circuits of Figs. 1, 2 and 3A.

Fig. 3C illustrates a modification of the circuit of Fig. 3B, in which an inductance coil 7h in series with a condenser 7i is shunted by a condenser 7j and by a parallel inductance 7k. The circuit of Fig. 3C is less difficult to adjust than the circuit of Fig. 3B. For adjusting the circuit of Fig. 3C, the inductance 7h and condenser 7i are disconnected and the condenser 7j and inductance 7k are tuned to the carrier frequency to afford maximum negative feedback, that is a reduction of gain at the carrier frequency. The inductance 7h and condenser 7i are then connected and tuned to pass the carrier frequency, the circuit then affording an approximately symmetrical cut-off of side-bands on each side of the carrier frequency.

The circuit shown in Fig. 3D is similar to that shown in Fig. 3C with the difference that the coil 7h is shunted by a condenser 7l which permits the use of a smaller inductance for the coil 7h. Typical values for the components of the circuit 3D are for a carrier frequency of

$$\frac{800000}{2\pi}$$

Inductance 7h	microhenries	3125
Condensers 7i and 7l	micro-microfarads	250
Inductance 7k	microhenries	31.25
Condenser 7j	micro-microfarads	50000

With components having the values stated, high impedance resonances occur at approximately 3200 cycles per second on each side of the carrier frequency. With coils in which

$$\frac{L}{R} = 200$$

where ω is the frequency in cycles per second, L the inductance, and R the resistance, the impedance of the circuit is about 50 ohms, at the carrier frequency and about 2,500 ohms at 3,200 cycles per second off the carrier frequency. A

valve having a slope of 4 milliamps per volt, will therefore lose 1.6 decibels gain at the carrier frequency and 20.8 decibels gain at a frequency 3200 cycles per second off the carrier frequency. A reduction of slope to 0.4 milliamps per volt will make the carrier loss negligible and at a frequency of 3,200 cycles per second off the carrier frequency the loss will be about 6 decibels. At 0.04 milliamps per volt, both losses will be negligible.

With the circuits shown, especially with that of Fig. 1, there may be a tendency for oscillation, since with a capacitive cathode load the input impedance of the grid (due to grid-cathode capacity) has a negative resistance component. In the construction shown in Fig. 4 (in which only the grid and cathode circuits are illustrated) a neutrodyning condenser 11 is provided to prevent such oscillation. The choke 8, which corresponds to the choke 8 of Fig. 1, is extended by a further portion giving a potential opposite to that of the cathode. The condenser 11 approximates to the grid-cathode capacity, assuming equal effective ratio for the two portions of the choke 8. Similarly, the inductance 1_k of Fig. 3D may be extended downwards and condenser 7_j correspondingly decreased so as to provide a neutrodyne potential. In practice, the inductance 1_k may with advantage consist of a small part of a much larger coil, the condenser 7_j being then bridged across the whole coil, thus requiring a much smaller value for condenser 7_j ; the neutrodyne voltage can then be obtained from a further tapping point along this coil.

Fig. 5 shows a further alternative which enables a less efficient circuit 7 to be used than that required by the arrangement of Fig. 1. The resistance of circuit 7 in Fig. 1 at resonance causes feed back at the carrier frequency, thus reducing the gain and reducing the difference of feedback for carrier and remote side-band frequencies. In Fig. 5 a tightly coupled and roughly tuned choke is provided having tappings 13, 14, 15 and 16 connected as shown. If the ratio between 13, 14 and 14, 15 is unity, and if resistance 12 equals the tuned resistance of circuit 7, no feed back will be produced at resonance, assuming negligible leakage inductance between 13, 14 and 14, 15, since the bridge will be balanced. At the side-band frequencies, however, negative feed back will be produced. The grid circuit decoupling condenser 3 may be connected at 15, but is preferably taken to a more remote tapping point 16 as shown. In effect, a step-up of feed back is obtained between the tapping points 14, 15 and 14, 16. This arrangement does not require such a high impedance for circuit 7, which might otherwise require an inconveniently high inductance/capacity ratio. To prevent oscillation, the neutrodyne condenser 11 may be provided connected to an extension 17 of the roughly tuned coil. If desired, the resistance 12 may be replaced by a parallel resonant circuit affording a resistance equal to resistance 12 at its resonant frequency and so serving to earth the tapping point 15 at frequencies remote from the carrier frequency. Many other alterations of this bridge circuit are possible. For example, the circuit 7 may even be replaced by a comparatively high resistance and the resistance 12 replaced by a parallel tuned circuit, thus obtaining a similar effect to that which results when the resistance 12 is replaced by a parallel resonant circuit as aforesaid. Similarly, the bridge circuit may be placed in the anode decoupling lead as in Fig. 2.

This would correspond to earthing the cathode and tapping 14, and returning the anode decoupling condenser to the junction of the circuit 7 and resistance 12. With the screen of the valve 6 earthed, tapping 17 and the neutrodyne condenser would not be required. If the decoupling condenser (not shown) usually associated with the screen of valve 6 were also returned to the junction of circuit 7 and resistance 12 (to increase the effective slope), then the tapping point 17 would require to lie on the other end of the choke, (beyond the point 13) and condenser 11 would neutrodyne the screen to grid capacity of the valve.

- 15 With the bridge circuits shown, small positive feed back may be introduced at the carrier frequency, as for example, by making the resistance 12 slightly greater than the resistance of the circuit 7 at its resonance. This, however, will not alter the operation, since for frequencies remote from carrier frequency the required selectivity will be obtained by introducing negative feed back, as against the positive feed back for the carrier frequency.
- 20 The invention may also be applied to receivers other than of the superheterodyne type, in which case the circuit 7 would be arranged to be tunable with the other circuits. Similarly the invention may be applied to more than one amplifier stage.

25 Fig. 6 shows the invention as applied to the mixing valve (a hexode valve being shown) of a superheterodyne circuit, the bias on the signal grid (the third grid from the cathode) of the mixing valve being varied by the application thereof of bias potentials derived from an automatic volume control circuit. In this figure the tuned input circuit is indicated by the reference numeral 1, automatic volume control potentials being applied through the resistance 4 from the line 5, the signal grid being decoupled to earth by condenser 3. The intermediate frequency anode circuit is indicated at 2. The screening grids are fed through a high impedance choke 8 a decoupling condenser being provided between the screening grids and cathode as shown. Local oscillations are fed between the cathode and the first grid of the mixing valve, the source of local oscillations being conventionally represented in the figure. The intermediate frequency anode currents flow through circuit 7 and cause negative feed back of intermediate frequency voltage between the signal grid and cathode. The circuit 7 is of the type shown in Fig. 3C so as to by-pass the radio frequency currents through the shunt condenser shown.

55 If desired, a switch may be arranged to remove the automatic volume control bias from a valve having selective feed back, to enable the selectivity to remain for large input voltages if required. However, the removal of the automatic volume control negative bias may cause too much output from the receiver, unless there is an efficient automatic volume control, operative also on earlier valves. The same switch may, therefore, be arranged to make the bias of the earlier valves more negative and so counteract this effect.

70 Fig. 7 shows a modification of the invention. In this figure the valve 6 having the negative feed back circuit 7 in its cathode lead is associated with a further amplifier valve 16. Automatic volume control bias potentials are applied to the grids of the two valves, the bias potential of the automatic volume control line in this case is arranged to be at a positive potential to earth for

maximum gain. The cathodes of the two valves 16 and 6 are given a positive potential by means of resistances 22 and 21 in their cathode leads. The resistance 22, however, is smaller than the resistance 21, but is connected to the high tension supply through a resistance 23 which supplies extra steady current to maintain the cathode of valve 16 positive. An increase of signal strength causes the automatic volume control line to become less positive or more negative, causing a drop in anode currents. A drop of the current in valve 6 effectively lessens the positive potential on its cathode and so counteracts the change of bias. A similar effect takes place in valve 16, but as resistance 22 is less than resistance 21, the effect is less marked, and so valve 16 is biased more negatively than valve 6. This prevents the selectivity decreasing too rapidly with increase of signal strength. An interchange of resistances 22 and 23 with resistance 21 would produce the reverse effect. Valve 16 may of course be a high frequency mixing valve or an intermediate frequency valve.

Fig. 8 of the drawings shows a combined automatic and manual selectivity control. The arrangements of the two valves 6 and 16 is similar to that shown in Fig. 7, the biasing resistances 21 and 22 in this case, however, being equal. The resistance 23 feeds current from the high tension supply to cathodes of the two valves shown through the potentiometer 24. By adjusting the point of connection of the resistance 23 and potentiometer 24 to the left, the positive cathode potential is increased on the first valve and decreased on the second so increasing the feed of the second valve and thus increasing the selectivity while keeping the gain approximately constant. It is also found with variable selectivity that it is advantageous to cut the very low modulation frequencies at the same time as cutting the very high modulation frequencies, in order to preserve a better balance of the sound output. The invention can be applied to perform this bias cut automatically at the same time as the higher modulation frequencies are cut. Fig. 9 shows such a circuit in which automatic volume control is also employed in conjunction with one of the low frequency amplifying stages to maintain the sound output substantially constant. This feature may be applied generally to low frequency amplifiers in order to provide tone adjusting means. In this circuit, 23^a represents the last intermediate frequency valve of a superheterodyne circuit, and 21^a and 22^a are coupled circuits arranged as shown, the circuit 21^a being connected to a source of anode current not shown. The anode 29^a of a double diode valve 24^a supplies automatic volume control voltage to the automatic volume control line 5, which voltage is developed across resistances 25, 26, 27 and 28 connected as shown. The automatic volume control bias potentials are applied by line 5 to one or more of the preceding stages, in which the circuit 7, for affording a negative feed back which varies with frequency, is associated with one or more of said stages as described above. The resistance 27 is comparatively small and is used with condenser 34 to decouple any possible modulation frequency arriving from resistances 27^a and 28 arranged between the cathode and earth of a low frequency amplifier valve 35 shown as a pentode. A "delay" for the automatic volume control is provided both by the voltage drop across the resistance 27^a, and also by the potentiometer 29, 30 connected to the high tension

supply, the cathode of valve 24^a being decoupled to earth by condenser 38. This latter potentiometer draws comparatively little current in comparison with the current of the low frequency amplifier valve 35. This valve obtains its bias through potentiometer 33, and resistance 31 from a tapping on the resistances 25, 26 and 27 across which the automatic volume control potentials are developed. The grid bias is decoupled to earth by a condenser 37. The word "delay" is not intended to imply any time delay but has the significance attributed to the word when employed in the term "delayed automatic volume control."

Suppose that a "delay" of 7 volts is provided on the cathode of valve 24^a, and suppose also that approximately 21 volts bias, not allowing for the change in potential of the cathode of valve 35, is required to reduce the preceding valves to their minimum sensitivity then there will be a change of signal strength over the whole automatic volume control range of 4:1. The tapping providing the grid bias of valve 35 is so chosen as to change the slope of this valve by about 4:1 in this range, so that the final output for the same modulation depth is maintained approximately constant. This involves a rather large current in valve 35, which may necessitate a transformer coupling to the output valve in place of the resistance capacity coupling shown, if overloading is to be prevented at the position of minimum slope. A rectified modulation input for valve 35 is obtained from the anode 29^b of diode 24^a across the load circuit 32 and potentiometer 33. Further smoothing may be introduced at this point if required in order to remove any intermediate frequency input to the valve 35. The cathode load of valve 35 is composed of resistances 27^a, 28 shunted by condenser 36. This combined resistance is preferably made several times the inverse of the mutual conductance or slope of the valve. If condenser 36 is not made sufficiently large, a loss of low frequencies will occur when the inverse of the mutual conductance of valve 35, in parallel with the cathode resistance is less than the impedance of the condenser at the low frequencies. This bass loss, will be much less marked when valve 35 has a low slope, since the impedance of condenser 35 will no longer be high compared with the slope. Thus an automatic cut-off of the bass frequencies will be obtained for distant stations in the same manner as the automatic cut-off of the high frequencies prior to the detector. If preferred, high frequency cut-off may also occur after the detector, as for example, by inserting an inductance in series with condenser 36, so as to introduce the negative feed back again for the higher modulation frequencies. This may be employed independently or in conjunction with the attenuation of the bass response. As the valve 35 does not change its slope (in the example given) as much as do the earlier variable mu valves, this high frequency cut-off cannot be made as sharp nor will it be found as satisfactory as the high frequency cut-off applied in the manner described in the preceding examples. Valve 35 may be one of the variable mu type or may be a valve with a substantially straight characteristic curve having a remote anode current cut-off.

The circuit shown in Fig. 9 is intended to operate so as to provide a potential on the automatic or gain control lead 5, which for weak signals, is positive with respect to earth. The control

valves must have cathode resistances which cause the cathodes at high feed to be yet more positive than this potential, so that the valves are not operating with the grids positive with reference to the cathodes. These cathode resistances may be shunted by condensers so as to remove any negative feed-back, or may be left unshunted so as to reduce overload effect in the valve by providing negative feed-back, or finally, the resistances may be constituted by a resistance of the circuit 7 used to provide automatic variable selectivity, the resistance being any resistance such as the choke 8 in Fig. 1, coils 7K in Figs. 3C, 3D, or the resistance 12 in Fig. 6.

In designing the circuit shown in Fig. 9, the value of combined resistance 27a and 28 is made sufficiently high to produce at maximum sensitivity the required drop in low frequency response for valve 35. Part of this resistance 28 is used to produce the standing positive potential on the lead 5 via the resistance 27 (decoupled by 34 and the resistances 26 and 25). The whole positive potential available on the cathode of 35 is used via resistance 29 to provide positive "delay" volts for the diode 24a as regards its anode 29a. In most cases it may be found that there is insufficient positive potential on the cathode of the valve 35, having regard to the positive potential already applied from resistance 28 to the anode 29a, in which event it is necessary to provide additional positive potential by means of the resistance 30 connected to H. T. positive supply. An alternative arrangement is to connect the right hand end of resistance 29 to earth and either increase resistance 29 or reduce resistance 30 to obtain the desired voltage.

In some cases, particularly with the arrangement shown in Fig. 5, it is possible to operate the circuits satisfactorily with considerably positive feed back at the carrier frequency, the feed-back still being positive despite variation in the slope of the valve. For remote side-band frequencies, however, the feed-back is negative.

In the following claims the term "carrier frequency" is intended to include not only the actual carrier frequency but also the carrier frequency modified to the intermediate frequency of a superheterodyne receiver or to a second intermediate frequency in a double superheterodyne receiver.

Various modifications and alterations may be made within the scope of the appended claims.

We claim:

1. In a modulated carrier signal transmission network, a tube provided with at least a cathode, signal grid and plate, a signal input circuit coupled to said grid and cathode for applying thereto a band of signal frequencies whose mid-band frequency is of a desired carrier frequency, an output circuit connected to the plate and cathode, said output circuit being tuned to said desired carrier frequency, a reactive network connected between the plate and cathode of the tube and being series resonant to the said carrier frequency whereby alternating voltage developed across the reactive network has a relatively low amplitude at said carrier frequency and increasingly higher amplitudes at modulation frequency components of the said band spaced from said carrier frequency, means for impressing said alternating voltage upon said signal grid in degenerative phase, and means for controlling the gain of said tube thereby to regulate the magnitude of said alternating voltage.

2. In a modulated carrier signal transmission

network, a tube provided with at least a cathode, signal grid and plate, a signal input circuit coupled to said grid and cathode for applying thereto a band of signal frequencies whose mid-band frequency is of a desired carrier frequency, an output circuit connected to the plate and cathode, said output circuit being tuned to said desired carrier frequency, a reactive network connected between the plate and cathode of the tube and being series resonant to the said carrier frequency whereby alternating voltage developed across the reactive network has a relatively low amplitude at said carrier frequency and increasingly higher amplitudes at modulation frequency components of the said band spaced from said carrier frequency, means for impressing said alternating voltage upon said signal grid in degenerative phase, and additional means for decreasing the said tube gain for strong signal reception thereby to decrease the said degenerative voltage amplitude at the spaced modulation frequencies.

3. In a modulated carrier signal transmission network, a tube provided with at least a cathode, signal grid and plate, a signal input circuit coupled to said grid and cathode, an output circuit connected to the plate and cathode, said output circuit being tuned to a desired carrier frequency, a reactive network connected between the plate and cathode of the tube and being series resonant to the said carrier frequency whereby alternating voltage developed across the reactive network has a relatively low amplitude at said carrier frequency and increasingly higher amplitudes at modulation frequency components of the modulated carrier band spaced from said carrier frequency, means for impressing said alternating voltage upon said signal grid in degenerative phase, and auxiliary means, responsive to carrier amplitude variation, for controlling the gain of said tube thereby to vary the amplitude of the degenerative voltage.

4. In a side band modulated carrier energy transmission system, an amplifier tube having at least a cathode, a signal grid and an anode, a carrier energy input circuit connected between the grid and a point of relatively fixed potential, a carrier output circuit connected to the anode, a reactive network connected between the cathode and said point, said network having an impedance which is zero at the carrier frequency and which progressively increases in value for the successive frequencies of the modulation side bands, and means for decreasing the gain of said tube automatically in response to an increase of carrier amplitude.

5. In a side band modulated carrier energy transmission system, an amplifier tube having at least a cathode, a signal grid and an anode, a carrier energy input circuit connected between the grid and a point of relatively fixed potential, a carrier output circuit connected to the anode, a reactive network connected between the cathode and said point, said network having an impedance which is zero at the carrier frequency and which progressively increases in value for the successive frequencies of the modulation side bands, means for decreasing the gain of said tube automatically in response to an increase of carrier amplitude, means for detecting carrier energy in said output circuit, means for amplifying detected energy, and means responsive to said gain decreasing means for controlling the frequency response of said amplifying means.

6. In a modulated carrier signal transmission

network, a tube provided with at least a cathode, signal grid and plate, a signal input circuit coupled to said grid and cathode, an output circuit connected to the plate and cathode, said output circuit being tuned to a desired carrier frequency, a reactive network connected between the plate and cathode of the tube and being series resonant to the said carrier frequency whereby alternating voltage developed across the reactive network has a relatively low amplitude at said carrier frequency and increasingly higher amplitudes at modulation frequency components of the modulated carrier band spaced from said carrier frequency, and means for impressing said alternating voltage upon said signal grid in degenerative phase, said tube including an auxiliary electrode, means for impressing upon said auxiliary electrode local oscillations whose frequency differs from the input circuit signal frequency by the value of said output carrier frequency.

7. In combination with a network including a transmission tube having at least a cathode, signal grid and anode, a modulated signal carrier input circuit connected between the grid and cathode, a signal output circuit connected between the anode and cathode, means for automatically controlling the selectivity of said network comprising a series resonant circuit common to the input and output circuits, said common circuit being tuned to the carrier frequency whereby alternating voltage developed thereacross is fed back to said grid in a negative phase and to a greater extent at modulation frequency components of the modulated carrier band than at said carrier frequency, and means responsive to a decrease in carrier amplitude for increasing the degree of negative feedback at said modulation frequencies.

8. In a side band modulated carrier energy transmission system of the type including at least a carrier-tuned amplifier, a demodulator and a modulation frequency utilization circuit, the method which includes impressing modulated carrier voltage upon the amplifier, deriving from the amplified voltage modulated carrier frequency voltage components whose magnitude is directly dependent on the spacing in the modulated carrier band of a modulation frequency component from the mid-band carrier frequency, combining the said components with the impressed modulated voltage in an opposing sense, demodulating the amplified voltage, transmitting the demodulated voltage through said utilization circuit, controlling the magnitude of said derived components inversely with the carrier amplitude variation, and controlling the frequency response characteristic of said utilization circuit in a sense such as to reduce the low modulation frequency response when said carrier amplitude is a minimum.

9. In a side band modulated carrier energy transmission system of the type including at least a carrier-tuned amplifier, a demodulator and a modulation frequency utilization circuit, the method which includes impressing modulated carrier voltage upon the amplifier, deriv-

ing from the amplified voltage modulated carrier frequency voltage components whose magnitude is directly dependent on the spacing in the modulated carrier band of a modulation frequency component from the mid-band carrier frequency, combining the said components with the impressed modulated voltage in an opposing sense, demodulating the amplified voltage, transmitting the demodulated voltage through said utilization circuit, controlling the magnitude of said derived components, controlling the frequency response characteristic of said utilization circuit, and maintaining said two controlling actions so related that the derived components are of maximum value and the response of the low modulation frequencies is a minimum in response to minimum amplitude of the carrier.

10. In a side band modulated carrier transmission system of the type comprising a modulated carrier voltage transmission network, a demodulator and a modulation frequency voltage transmission network, means at said carrier transmission network for controlling the magnitude of the high modulation frequency components of the carrier side bands, means at said modulation transmission network for concurrently controlling the magnitude of the low modulation frequencies, and means common to said both control means for relating them in a manner such that the magnitudes under control are decreased in response to carrier amplitude decrease.

11. In a system for the transmission of side band modulated carrier voltage, and having a tube providing carrier voltage input and output circuits, the method which includes impressing modulated carrier voltage upon the input circuit, deriving from modulated carrier voltage repeated by the tube alternating voltage predominantly of the higher modulation frequency components of the carrier side bands, combining the derived voltage with the impressed voltage in a sense to reduce the response at the input circuit to said higher components, developing at the output circuit carrier voltage with reduced higher modulation frequency component magnitude, and regulating the magnitude of said derived voltage automatically in response to carrier amplitude variation thereby to adjust the magnitude of said response reduction.

12. A superheterodyne carrier wave receiver comprising an input circuit, a local oscillator circuit, an electronic tube for mixing the incoming oscillations with the locally generated oscillations, a second electronic tube for amplifying the intermediate frequency produced, a negative feed-back channel associated with at least one of said electronic tubes, and a resonant circuit tuned to the desired frequency to render the negative feed-back channel substantially ineffective at said desired frequency.
